METHOD OF MINING AND APPARATUS
THEREFOREdgar M. Cadwallader, Cleveland, Ohio, assignor
to Mineral Cutting Machine Company, Inc.,
Cleveland, Ohio, a corporation of Delaware

Application June 13, 1935, Serial No. 26,457

35 Claims. (Cl. 262—1)

This invention relates to a method of mining coal or similar mineral and an apparatus therefor. More particularly, the invention relates to the pitch mining of hard coal or similar mineral.

Pitch mining as now practiced consists in drilling holes into the face or breast of the coal at suitably spaced points, filling the holes with explosives, and then setting off the charges of explosives. In other words, the coal is broken from the face or breast by blasting. In this method the degree of impact and shattering power of the blast is dependent upon the skill exercised by the miner in selecting the proper relative positions for each hole, in drilling the holes to the proper depth, in employing the correct amount of the explosive charge, and in tamping the charge properly in each of the holes. Thus, it will be apparent that if great care and skill is not exercised by the miner, a blasting effect will result which is of such intensity and repercussion as to cause severe fractures in the lateral ribs and cave-ins in the roof and shatter the coal into a relatively high percentage of small particles of a size known as undersized coal or fines. Further, the coal is blasted primarily from the central portion of the breast, leaving portions of the coal depending from the roof and protruding from the lateral ribs. In order to maintain the breast or face of uniform fracture, it is necessary to remove such portions, and this can only be done by hand-operated wedges, sledges, or picks. As a matter of fact, it is not possible to dislodge the coal by blasting from the entire area of the breast or face without causing some damage to the roof and the lateral ribs.

In the blasting method of pitch mining, it is necessary to continually reinforce the roof by means of upright timbers and collars so as to protect the workmen from injury or fatality due to the falling of pieces or sections of the roof. The timber required for this purpose can only be brought up to the workman in the breast through the man-ways, and this is an extremely difficult and burdensome task, because of the great weight of the timbers. Furthermore, the blasting causes an undue amount of smoke and coal dust which are not only injurious to the health of the workman, but also unduly tax the system of ventilation. In addition, there is the grave danger of gas explosions and consequent fires which result in many injuries or fatalities to the workman. Then again, this method of mining produces approximately 35% of what is known as undersized coal or fines of each ton

mined which undersized coal or fines can only be sold at a price below the production cost.

Accordingly, an object of the present invention is to provide a method of pitch mining wherein the coal or similar mineral is mined without blasting.

Another object of the present invention is to provide a method of pitch mining without blasting wherein the coal or similar mineral is broken away and dislodged by the application to the walls of contiguous communicating areas at points intermediate the axes of said areas formed in the working breast at a point spaced from an undercut and side cut in the breast of expansive forces which in themselves are of such magnitude as to break away the coal or mineral in the region of such areas in sizable pieces with a minimum of fines and undersized particles.

Another object of the present invention is to provide a method of pitch mining without blasting wherein the coal or similar mineral is broken away and dislodged by the application to the walls of contiguous communicating areas at points intermediate the axes of said areas formed in the working breast at a point spaced from an undercut and side cut in the breast of expansive and vibratory forces which in themselves are of such magnitude as to break away the coal or mineral in the region of such areas in sizable pieces with a minimum of fines and undersized particles.

A further object of the present invention is to provide a method of pitch mining without blasting which enables coal or similar mineral to be mined in greater quantities of sizable pieces per unit ton than is possible by the pitch mining employing blasting.

A still further object of the present invention is the provision of an apparatus for the mining of coal or similar mineral which is comparatively light in weight, easy to install in the working breast, and simple to operate.

A still further object of the present invention is the provision of an apparatus for the mining of coal or similar mineral wherein a plurality of boring elements arranged in spaced and aligned relation are capable of attacking the face of the breast in any plane which is substantially parallel with the pitch of the floor of the vein.

Still another object of the present invention is the provision of an apparatus for the mining of coal or similar mineral which is capable of performing all of the operations incident to the mining of coal or similar mineral from the working breast without the use of explosives.

Briefly stated, the method according to the

55

present invention comprises forming a fissure in the breast at an angle substantially parallel to the pitch of the floor at the juncture point of the breast and floor of the vein, fracturing the cleavage of the coal or mineral from the floor to the roof of said vein along the joinder point of a lateral rib and the breast, forming contiguous communicating areas of a depth substantially corresponding to said fissure in the breast in a plane spaced from said fissure which is substantially parallel to the pitch of the floor, and applying to the walls of said areas at points intermediate the axes of said areas expansive forces which in themselves are of sufficient magnitude to break away and dislodge the coal or mineral in the region of said areas in sizable pieces with a minimum of fines and undersized particles.

The fissure may be formed by boring into the face of the breast at the juncture point of the breast and the floor of the vein at an angle substantially parallel to the pitch of the floor to the desired depth. This may be done by causing a series of aligned boring elements to simultaneously bore into a portion of the breast to the desired depth, withdrawing the boring elements, and successively repeating such boring and withdrawing operations upon other portions of the face until the fissure extends partially or completely across the entire width of the breast. Preferably, the fissure is made so that it extends completely across the entire width of the breast. The depth of the fissure is variable, it being dependent upon the length of the boring elements employed. Boring elements of a length just sufficient to bore to a depth of from $3\frac{1}{2}$ to 4 feet have been found to be most satisfactory. Although a depth of $3\frac{1}{2}$ to 4 feet is preferred, it is to be understood that satisfactory results are obtained if the depth of the fissure is less than $3\frac{1}{2}$ feet. The formation of the fissure severs or fractures the cleavage between the bed rock of the floor and the coal or mineral to be mined.

The fracturing of the cleavage of the coal or mineral along the joinder point of a lateral rib and the breast may be effected in the same manner as previously described in the formation of the fissure or in such manner that the coal is just punctured sufficiently at a plurality of spaced points along the joinder point from the floor to the roof of the vein so as to sever or break the cleavage of the coal or mineral at such point. Preferably, the cleavage of the coal or mineral is severed along the joinder point of both the lateral ribs and the breast.

The application of the expansive forces to the breast or face of the coal or mineral which are of sufficient magnitude in themselves to break away and dislodge the coal or mineral in sizable pieces with a minimum of fines and undersized particles may be effected in a number of ways. One manner of doing this consists in contacting a plurality of aligned and spaced boring elements with the face of the breast in a plane spaced above the fissure which is substantially parallel to the pitch of the floor of the vein, and causing the boring elements to bore into the coal to thereby form contiguous communicating areas. Preferably, the boring elements are provided with boring bits of the type such as to partially overlap each other so as to produce a series of spaced localized areas which are in the form of circular holes interconnected to each other by means of passages whose upper and lower walls simulate a V-shaped rib. As the boring progresses, expansive forces are applied to the walls of each

of the passages connecting the circular holes, preferably successively and at periodic intervals. These expansive forces may be induced by causing jaw members to be pressed against the walls of the aforesaid passages, preferably at points spaced therealong. The selection of the plane above the fissure at which the boring elements are to penetrate the coal or mineral depends upon the depth of the fissure and the texture and solidity of the coal or mineral. While it is preferred to have the plane of penetration at a distance of from 1 to 3 feet from the fissure, it is also possible to have the spacing of such plane more or less than the aforesaid distance. The aligned boring elements are preferably of a length sufficient to bore holes of a depth substantially corresponding to that of the fissure and of an overall width corresponding to a multiple of the entire width of the breast, for example, two feet.

In some instances, it is desirable and advantageous to apply both expansive and vibratory forces to the walls of the contiguous communicating areas at points intermediate the axes of said areas. This may be done by causing the jaw members to be pressed against the walls of the passages interconnecting the circular holes as the boring progresses and intermittently applying hammer blows to either the boring elements or the jaw members.

The boring action of the boring elements with the boring elements equally spaced from each other penetrates the coal and thereby forms contiguous communicating areas from which the expansive forces exerted through the jaw members upon the walls of the interconnecting passages are distributed to the coal or mineral in the region of each of such areas to an extent sufficient to cause the breaking away and dislodging of the coal. Where the expansive forces are supplemented by the vibratory forces which are exerted through the boring elements or the jaw members these vibratory forces are likewise distributed to the coal or mineral in the region of said areas.

Inasmuch as the overall width of the spaced boring elements is but a multiple of the entire width of the breast, this same treatment which results in the formation of contiguous communicating areas and the application of expansive forces alone or both expansive and vibratory forces to such areas is continued successively along the same plane until the entire width of the breast has been thus treated. This same operation is successively repeated along other suitably spaced planes until the entire face of the breast of coal or mineral has been broken away and dislodged.

An embodiment of an apparatus for use in carrying out the method according to the present invention is illustrated in the accompanying drawings, wherein—

Figure 1 is a side elevation showing the apparatus according to the present invention in operative position in a coal or mineral vein of the pitch type.

Figure 2 is a plan view taken on the line A—A of Figure 1.

Figure 3 is a side elevation view in section, taken on the line B—B of Figure 2, showing the mechanism for actuating the boring elements and the elements for inducing the expansive forces, and the mechanism for adjusting these elements as a unit to any desired position.

Figure 4 is a side elevation in section, taken

Figure 21 is a partial plan view of Figure 20 showing the nests of driven gears in association with the speed change gear.

Figure 22 is a detailed side elevation view in section taken on the line S—S of Figure 20, showing the mechanism for locking the speed change gear in its adjusted position.

Figure 23 is an end view in section, taken on the line T—T of Figure 3, showing the keys for locking the telescopic tubes to each other when rotated.

Figure 24 is an enlarged side sectional elevational view showing the telescopic tubes for connecting the shaft for rotating the boring elements and for feeding the boring and expansive force inducing elements forward and backward as shown in the lower portion of Figure 15 with the shaft for actuating the gearing for rotating the boring elements as shown in Figure 3.

Figure 25 is an enlarged detailed end view in section, taken on the line U—U of Figure 24, showing the configuration of the nut on the shaft for operating the clutch member for actuating the expansive force inducing elements.

Figure 26 is an end elevation view in section, taken on the line W—W of Figure 1, showing the mast structure for supporting the mechanism for operating the boring elements in the vein, and the mechanism for mounting same.

Figure 27 is an end elevation view in section, of the top of the mast structure of Figure 1 showing the manner in which the mast is connected to the trolleys.

Figure 28 is an enlarged end elevation view in section, taken on the line V—V of Figure 1, showing the mounting of the carriage supporting the machine upon the tracks and the mechanism for moving the carriage along the tracks.

Figure 29 is an enlarged plan view, partly in section, taken on the line X—X of Figure 1, showing the jack for moving the carriage along the tracks.

Figure 30 is an enlarged elevational view in section, taken on the line Y—Y of Figure 29, showing the connection of the jack with the carriage.

Figure 31 is a side elevation view, partly in section, taken on the line Z—Z of Figure 30, showing the specific manner of attaching the jack to the carriage frame.

Figure 32 is a side elevation view in section, of a modification of the structure shown in Figure 3, showing the mechanism for applying vibratory forces to the elements for inducing expansive forces.

Figure 33 is a partial plan view in section, taken on the line A’—A’ of Figure 32, showing the mechanism for applying hammer blows to the elements for inducing expansive forces.

Figure 34 is a side elevation view showing the manner of connecting the hollow sleeve to the rod operating the expansive force inducing elements.

Referring to the drawings, the numeral 1 designates the device for boring into the coal or mineral and applying expansive forces thereto. Such device comprises a housing 2 from

which protrude a series of boring elements 3. The boring elements 3 are rotatably mounted in the housing 2. As the mounting of each of these elements is the same, only one of such 5 mountings will be described. The boring element 3 is mounted in bearings 4, 5, and 6 of the housing 2 as shown in Figure 3. Fixedly secured to the boring element 3 intermediate the bearings 5 and 6 is a pinion 7 which meshes 10 with a gear 8 carried by a shaft 9. The gear 8 in turn meshes with a gear 10 carried by the shaft 11. The gear 10 meshes with the pinion 12 fixedly mounted on a hollow hexagonal shaft 13 as shown in Figure 4.

15 To one end of the hollow hexagonal shaft 13 is coupled a hollow tube 14 by means of the coupling 15. The tube 14 is of larger cross-sectional area than the shaft 13 as clearly shown in Figure 3. Telescoping into the free end of 20 the tube 14 is a hollow tube 16 which is slidably keyed thereto. The hollow tube 16 extends through the projection 33 of the transmission case 17 and is rotatably mounted therein. On this tube 16 is mounted a gear 18 which meshes 25 with a gear 19 carried by a shaft 20. Mounted upon the shaft 20 and fixedly keyed to the gear 19 is a gear 21 which meshes with a gear 22 carried by a shaft 23. The shaft 23 also carries a gear 24 which meshes with a pinion 25 carried by the shaft 26 of the motor 27.

Surrounding the portion of the hollow tube 16 which is mounted in the transmission case 17 is a sleeve 28. Mounted in surrounding relation with the sleeve 28 is a hollow tube which 35 comprises a non-threaded portion 29 and a threaded portion 30 as clearly shown in Figures 15 and 24.

In threaded engagement with the threaded portion 30 is a travelling nut 31 which is fixedly 40 secured to the inner peripheral surface of a hollow tube 32. On the threaded portion 30 at a point suitably spaced from the nut 31 is a collar 34 which acts to maintain the threaded portion 30 in aligned position within the tube 32. The 45 end of the tube 32 opposite the travelling nut 31 extends into the projection 34' of the housing 2 of the boring and expansive force applying device 1 and is fixedly secured thereto by suitable bolts 35 as shown in Figure 3. In surrounding relation and in slidable engagement 50 with the tube 32 is a sleeve 36 which has one end extending into the projection 33 of the transmission case 17 and is fixedly secured thereto by suitable bolts 37.

55 On the non-threaded portion 29 of the hollow tube are keyed a nest of gears 38, 39, 40, 41, and 42 which are of varying diameters as shown in Figures 15 and 24. Carried by a shaft 43 are a nest of gears 44, 45, 46, 47, and 48 which are likewise of varying diameters. This last-named nest 60 of gears is in alignment with but in reverse complementary relation with nest of gears 38, 39, 40, 41, and 42. A gear 49 carried by a loose shaft 50 is shiftable to a position such that it will mesh with 65 any pair of opposed gears of the respective nests of gears previously described. For example, it may be made to mesh with gears 40 and 46 as clearly shown in Figures 20 and 21. The mechanism for shifting the loose shaft 50 to the meshing position desired for the gear 49 with the opposed pair of nest of gears comprises a bearing 51 provided with a forked extension 52 carried by the shaft 50 which forked extension engages with and rides along an angular track 53. The bearing 75 51 has a loose collar 54 which is secured there-

to by means of a pin 55. Extending through the collar 54 is a slidable arm 56 which is secured to one end of a pin 57 mounted in the lower portion of the transmission 17, surrounding the pin 57 and bearing against the arm 56 and the inside surface of the transmission case 17 is a spring 58. To the opposite end of the pin 57 is secured an arm 59 which has its free end locked to the transmission case 17 by means of a pin 60 being inserted in any one of the holes 61 in the transmission case as shown in Figures 20 and 22. The holes 61 are spaced in such manner as to correspond with the meshing position of gear 49 with any one of the opposed pairs of the respective nests of gears. On the top of the pin 57 is securely fixed a knob 62 for operating the pin and arm 59. The pin 57 is provided with a cut out portion 63 which receives the end of locking pin 64 extending through an opening in the transmission case 17 as shown in Figure 22.

20 On the shaft 43 carrying the nest of gears 44, 45, 46, 47, and 48 there is also mounted a gear 65 which meshes with a gear 66 attached to and forming a part of the loose part of the forward friction disk clutch 67 loosely mounted on the shaft 68. The shaft 68 also carries a gear 69 which meshes with a pinion 70 carried by the shaft 23. The shaft 23 is connected to the pinion 25 of the motor shaft 26 through the medium of gear 24 as previously described.

25 The shaft 43 also carries a gear 71 which meshes with an intermediate gear 72 carried by the stub shaft 13. The gear 72 in turn meshes with a gear 74 which is attached to and is a part of the loose part of the reverse friction disk clutch 75 loosely mounted on shaft 68 as shown in Figures 16 and 17. The shaft 68 is connected to the pinion 25 of the motor shaft 26 through the medium of gear 69, pinion 70, and gear 24 on shaft 23.

30 On shaft 68 in complementary relation with the loose part 67 of the forward friction disk clutch is fixedly mounted the slidable part 76 of such friction disk clutch which is connected to one end of a rod 77 by the pin and yoke connection 78. To the opposite end of said rod 77 which protrudes 35 out of the transmission case 17 is secured a hand lever 79 which is pivotally connected to a brace member 80. The hand lever 79 is for the purpose of operating the clutch.

35 On the shaft 68 is also fixedly mounted the 40 slidable part 81 of the reverse friction disk clutch in complementary relation with the loose part 75 of such clutch. The slidable part 81 is connected to one end of the hollow tube 82 by means of the pin and yoke connection 83. As shown in Figures 16 and 19 the tube 82 is in surrounding relation 45 with respect to rod 77, and has its opposite free end protruding out of the transmission case 17 to which is secured a hand lever 84, said lever being pivotally connected to a brace member 85. The hand lever 84 operates the reverse clutch.

50 As shown in Figure 16 the tube 82 is provided 55 with collars 86 and 87 disposed adjacent the yoke members 78 and 83 respectively. Attached to the collar 86 and bearing against yoke connection 78 is a compression spring 88, and a compression spring 89 having an end attached to the collar 87, bears against yoke connection 83. Engaging 60 with the tube 82 and movable therealong is a forked member 90 which is secured to a threaded shaft 91 which carries a sprocket 92 on one end thereof. In engagement with the sprocket 92 and extending to and engaging with a sprocket 93 carried by the end of the non-threaded hollow tube portion 29 is a sprocket chain 94. The forked 70 75 75

member 90 is moved forward or backward along the tube 82 by this sprocket mechanism until it bears against either of the collars 86 or 87 depending upon whether the forward or reverse clutch is in operative relation to automatically disengage the respective clutch.

As will be apparent from Figures 2 and 5 the boring elements 3 are suitably spaced from each other and are in aligned relation. Disposed intermediate each pair of the boring elements 3 is an expansive force inducing element. As the structure of the expansive force inducing elements is the same, only the structure of one of such elements will be described. The expansive force inducing element comprises a square shaped hollow tube 95 provided with slots 96, 97, and 98 which extend through the opposite walls of the tube as clearly shown in Figures 5 and 6. Within the tube 95 is disposed a rod 99 which is provided with enlarged threaded portions 100, 101, and 102 suitably spaced therealong as shown in Figure 5. In threaded engagement with each of the enlarged threaded portions 100, 101, and 102, is a squared nut 103 having a pointed nose 104 which is slidable in the tube 95 as shown in Figure 6. Inasmuch as the squared nuts 103 are of the same structure only two are shown in detail. Within the tube 95 adjacent each of the slots 96, 97, and 98 is mounted and fixedly secured thereto a squared block 105 such as shown in Figure 6. Each of the blocks 105 is provided with ears 106 and 107 to which are pivotally connected jaw members 108 and 109 which cooperate with the pointed nose 104 of the squared nut 103. Each pair of jaw members 108 and 109 operate through the respective slots 96, 97, and 98. The pair of jaw members 108 and 109 operating through the slots 96 and 97 are of the configuration shown to the left of Figure 6 while the pair of jaw members operating through slot 98 are of the configuration shown to the right of said figure. The ends of the jaw members 108 and 109 are pivotally connected to the nose portion 104 of the squared nut 103 as at 110 by means of slotted levers 111 and 112.

The series of square shaped hollow tubes 95 are supported intermediate each pair of the boring elements 3 in aligned relation therewith by having one end of the tube secured to the housing 2 by means of clip angles 113 and the opposite end extending through and secured to a cross bar 114 as shown in Figures 5 and 12.

The free end of the rod 99 carrying the expansive force inducing elements extends through an opening into the housing, and is mounted in bearings 115 and 116. On the rod intermediate the bearings 115 and 116 is fixedly mounted a sprocket 117 as shown in Figure 12. As shown in Figure 11 there is a series of such rods 99, each of which carries a sprocket 117. Each of these sprockets 117 is in engagement with a sprocket chain 118 which is driven by a sprocket 119 carried by a sleeve 120, one end of which is mounted in the housing 2 as at 121. The other end of the sleeve 120 is mounted in a bearing 122. The sleeve 120 adjacent the bearing 122 carries a loose part 123 of a friction disk clutch which is slidably secured to said sleeve by means of pin 124, said pin passing through an opening in the rod 126 and opposed slots in the sleeve 120. As shown in Figure 24, the loose part 123 of the friction disk clutch cooperates with a fixed part 125 of a friction disk clutch which is mounted upon the other end of the hexagonal hollow shaft 13.

The rod 126 has a threaded end 127 on which is fixedly secured a collar 128. Mounted on the threaded end 127 is also a threaded hexagonal nut 129. As shown in Figures 24 and 25, the threaded end 127 extends into a thimble 130 whose interior surface is hexagonal in shape, the thimble being secured to the housing 2. It is to be noted that the cross-sectional area of the hexagonal shaped nut 129 is slightly larger than that of the sleeve 120 as shown in Figures 24 and 25. To the opposite end of the rod 126 is secured a hollow tube 133 by means of a pin 131, which pin engages with and rides in a slot 132 in said tube as clearly shown in Figure 34. Upon pulling the wheel 134 backward the rod 126 is moved backwardly so that the loose part 123 of the clutch engages with the driven part 125 of the clutch and thereby causes the rotation of the rod 126 through sprocket 119, and sprockets 117, and chain 118. Simultaneously the nut 129 travels along the threaded portion 127 until it abuts against the end of the sleeve 120 whereupon it disengages the loose part 123 from the driven part 125 of the clutch and stops the rotation of the rod 126. When the rotation of the rod 126 is stopped, the wheel 134 is turned in the opposite direction to rotate the rod 126 in a reverse manner and thereby cause the nut 129 to move backwardly along the threaded portion 127 of rod 126 and rotate the rods 99 in the opposite direction through sprocket 119, sprockets 117, and chain 118 to move the jaw members 108 and 109 to their initial position.

The boring elements 3 are provided with boring bits 135 which are of a configuration such that they partially overlap each other as shown in Figure 5. This enables the formation of spaced localized areas in the breast of coal or mineral which are in the form of circular holes interconnected to each other by means of passages whose upper and lower walls simulate a V-shaped rib as clearly shown by the dotted lines in Figure 10. It is apparent that these passages permit the tubes 95 carrying the expansive force inducing elements to enter into the breast of coal or mineral with the boring elements 3.

Mounted upon the sleeve 36 is the mechanism for moving the boring and expansive force inducing device 1 as a unit to a position such that the boring elements will be in either a horizontal or vertical plane. Such mechanism comprises a sleeve 136 rotatably mounted on the sleeve 36. Secured to the sleeve 136 is a gear case 137 which houses a worm gear 138 meshing with a worm 139 carried by shaft 140 which also carries a hand wheel 141. Adjacent the gear case 137 and rotatably mounted on sleeve 36 is a collar 142 which is provided with openings spaced about its periphery. As shown in Figure 23, there are three openings in said collar 142 through each of which extend keys 143, said keys also extending through complementary slots in sleeve 36 and riding upon grooves 144 in tube 32. The keys 143 are provided with set screws 144' for adjusting the mounting of the keys in the slots.

The apparatus comprising the combined boring and expansive force inducing device 1 and the transmission case 17 housing the actuating means for said device is connected to a supporting mast 146. The means for connecting such apparatus to the supporting mast comprises the sleeve 136 and the supporting collar 145 mounted upon the sleeve 36. Sleeve 136 is pivotally connected to a sleeve 145 surrounding the lower portion of the mast 146 and in sliding engagement therewith

by means of a collar 147 and pin 148. The supporting collar 145 is connected by a fork 149 to a bearing collar 150 which is pivotally connected to the sleeve 145' by the pin 151. The fork is 5 provided with a threaded handle 152 which extends through the bearing collar 150. A nut 153 is in threaded engagement with the threaded handle 152, and this nut acts to raise and lower the apparatus about the pivot pin 151. By reference to Figure 1 it will be seen that the nut 153 bears against the bearing collar 150 and thereby holds the apparatus in position on the mast. By turning the nut 151 to the right the apparatus will be tilted upwardly and by turning the nut 15 to the left the apparatus will be tilted downwardly to the degree desired.

The mast 146 comprises hollow tubular sections 154 and 155 which telescope into each other. The sleeve 145' surrounds the section 154 and is 20 slideable thereon. Each of said sections are provided with openings in the sides thereof as shown in Figure 26 for adjusting the relative positions so as to increase or decrease the overall length of the mast. The sections are locked in the adjusted position by means of pins or bolts 156. The lower end of the section 154 extends into a socket 157 of a trolley frame 158. The trolley frame 158 is provided with wheels 159 and 160 which ride along the top of a transversely disposed track 161, said track being secured to the side beams 162 and 163 of a carriage 166 as at 164 and 165. Carried by the trolley frame 158 are thrust wheels 167 and 168 which ride along the web of the track 161 as shown in Figure 26.

35 The top of the section 155 of the mast 146 is connected to a bracket 169 which carries a trolley 170. The trolley 170 rides along a transverse track 171 disposed adjacent the top of the vein which track is connected at its opposite ends 40 to the top of telescopic supports 172 and 173 by means of brackets 174 as shown in Figures 1 and 2. The lower ends of each of the supports 172 and 173 are connected to side beams 162 and 163 45 of the carriage 166 by means of brackets as at 175 and 176.

By applying a pushing force to the right or left of the mast 146, the mast which carries the apparatus for boring and applying expansive forces 50 to the coal or mineral is caused to travel back and forth along the transverse tracks 161 and 171.

The mechanism for raising and lowering the apparatus for boring and applying expansive forces while supported on the mast 146 comprises 55 a threaded rod 177 having its upper end secured to the bracket 169 as at 178 as shown in Figure 27. The rod 177 passes through a threaded nut 179 carried by a collar 180 which is mounted on the sleeve 145' of the mast 146, and extends into a hollow tube 181, said tube being supported by bearings 182 and 183 carried by the trolley frame 158. The portion of the threaded rod 177 enclosed by the tube 181 is provided with a key 60 way 185 in which slides a key 184 protruding from the interior surface of said tube and a part thereof. Mounted upon the trolley frame 158 is a gear case 186 through which extends the tube 181 as shown in Figure 26. Fixedly mounted upon 65 the portion of the tube 181 within the gear case 186 is a gear 187 which meshes with a gear 188 carried by the shaft 189 having a hand wheel 190 mounted on the end thereof. By turning the hand wheel 190 it will be apparent that the 70 threaded rod 177 will be rotated through the me-

dium of shaft 189, gears 188 and 187 and thereby cause the rod 177 to move the nut 179 and collar 180 supporting the apparatus up and down along the mast 146, depending upon the direction in which the wheel 190 is turned.

Referring to Figures 1 and 2 the carriage 166 is provided with wheels 191 which ride along tracks 192 longitudinally disposed along the floor of the vein. The wheels 191 are connected to the side beams 162 and 163 by brackets 193 and 194. The tracks 192 set in boots 195 and 196 and are fixedly secured thereto. To the sides of each of the boots 195 and 196 are secured yokes 197 to which are attached the lower ends of telescopic tubes 198. The upper ends of the telescopic tubes 198 engage with the roof of the vein and are anchored thereto by means of claw shaped shoes 199. The boots 195 are provided with an extension 200 in which is disposed one end of a jack 201. The opposite end of the jack 201 is connected to bracket 193 as shown in Figures 28, 29, 30, and 31. By turning the threaded rod 202 the threaded nut 203 travels forward or backward along the rod 202 depending upon the direction in which the said rod is turned, and thereby causes the inner tube 204 to move forwardly or backwardly within the outer tube 205 to push the bracket 193 and wheels 191 of the carriage 166 supporting the mast 146 carrying the apparatus up or down along the tracks 192. The tracks 192 are provided with means for locking the carriage 166 at the stopping position, such means comprising a dog 207 carried by brackets 208 secured to side beams 162 and 163 of the carriage 166 which engages with a toothed rack 206 fixedly secured to the top of tracks 192 as shown in Figures 1, 28, and 30.

In carrying out the method of the present invention with the apparatus thus described, the operator shifts the mounting of the boring and expansive force inducing device 1 to a position such that the boring elements are in a horizontal plane. This is done by turning the hand wheel 141 in the proper direction to a degree sufficient to cause the sleeve 36 to rotate within the sleeve 136 carrying the housing 2 of the boring and expansive force inducing device 1 by means of the shaft 140, worm 139, and worm gear 138. With the rotation of the sleeve 36, the collar 142 is likewise rotated thereby causing the keys 143 to ride along the grooves 144 in tube 32. These keys act to retain the sleeve 36 in the position to which it has been moved by its rotation within the sleeve 136.

With the boring and expansive force inducing device 1 in position such that the boring elements are in a horizontal plane, the operator next shifts the apparatus comprising the combined boring and expansive force inducing device 1 and the transmission case 17 housing the actuating means for said device to a position such that the boring elements will be in a horizontal plane which is at an angle substantially parallel with the pitch of the floor of the vein. This is effected by turning the nut 153 to the right to a degree sufficient to cause said nut to travel along the threaded handle 152 of the fork 149 and thereby tilt the apparatus upwardly about the pivot pin 148. As the nut 153 is in constant engagement with the bearing collar 150 it also acts to hold the apparatus in its adjusted position.

After the boring and expansive force inducing device 1 is in position such that the boring elements are in a horizontal plane which is at an angle substantially parallel with the pitch of the

floor of the vein, the operator lowers the apparatus to a point such that the boring elements in their adjusted position face a multiple of the breast at the juncture point of the breast and 5 the floor of the vein. This is done by turning the hand wheel 190 in the proper direction to a degree sufficient to cause the threaded rod 177 to be rotated through the medium of shaft 189, gears 188 and 187, thereby moving the nut 179 and 10 collar 180 supporting the apparatus downwardly along the mast 146.

The operator next applies a pushing force to the right or left of the mast 146 to shift the apparatus for boring and applying expansive forces 15 to the coal or mineral to a point such that the boring elements are in position to attack a multiple of the working breast extending from either one of the two lateral ribs or intermediate the two lateral ribs. Preferably, the apparatus is 20 shifted to a point such that the boring elements will attack a multiple of the working breast extending from either the right or left hand lateral rib.

When the boring elements are in position to 25 attack a multiple of the breast extending from one of the lateral ribs, the operator starts the rotation of the motor shaft 26. The rotation of the shaft 26 causes the rotation of each of the boring elements 3 through the pinions 7 carried 30 by each of said elements. As shown in Figure 4, the pinions 7 are in mesh with each other, and such pinions are rotated in unison by means of a gear 8 which meshes with one of the pinions 7. The gear 8 is driven from the motor shaft 26 35 through shaft 9, gear 10, shaft 11, pinion 12, hollow hexagonal shaft 13, hollow tube shafts 14 and 16, gear 18, gears 19 and 21, shaft 20, gears 22 and 24, shaft 23, and pinion 25.

While the boring elements 3 are rotating, the 10 operator pushes the hand lever 79 inwardly so as to cause the feeding of the rotating boring elements into the breast of coal or mineral. The pushing of the lever 79 inwardly moves the driven part 76 of the friction clutch into engagement with the loose part 67 of the friction clutch and thereby rotates shaft 43 through the medium of gears 66 and 65. The shaft 43 drives the hollow tube shaft 29 by means of gear 46, 49, and 40. By the rotation of the hollow shaft 0 29 the nut 31 is caused to move along the threaded portion 30 of the shaft 29, and thereby feed sleeve 32 carrying the boring and expansive force inducing device 1 forwardly into the breast of coal or mineral. The extent of travel forwardly of the nut 31 along the threaded portion 30 of the hollow shaft 29 is controlled by means of the travelling yoke 90 which moves along tube 82 and threaded shaft 91 and contacts with and bears against the yoke connection 78 attached to 5 the driven part 76 of the friction clutch at a certain point in its travel to disengage the driven part 76 from the loose part 67 of the clutch. As shown in Figures 13, 14, and 16, the travelling yoke 90 is caused to move forwardly along the threaded shaft 91 by means of sprocket 92, sprocket chain 94, and sprocket wheel 93.

The feeding of the boring elements into the face of the breast causes a plurality of spaced 0 holes to be formed therein. Since the auger bits 135 of the boring elements 3 are of such configuration that they partially overlap each other, the boring elements form spaced localized areas in the coal which are in the form of circular holes inter- 5 connected by passages whose opposite walls simu-

late V-shaped ribs as clearly shown by the dotted lines in Figure 10.

When the boring elements have penetrated into the coal to the desired extent which is controlled by the disengagement of the driven part 76 from the loose part 67 of the clutch by means of the travelling yoke 90, the operator pushes the lever 84 inwardly so as to cause the feeding of the rotating boring elements away from the breast. The pushing of the lever 84 inwardly moves the driven part 81 of the reverse clutch into engagement with the loose part 75 of the clutch, and thereby rotates shaft 43 reversely through gears 14, 72, and 71. The shaft 43 drives the hollow tube shaft 29 by means of the gears previously described for rotating shaft 43 in the opposite direction to thereby feed sleeve 32 carrying the boring and expansive force inducing device 1 backwardly and away from the breast of coal or mineral. The extent of travel of the nut 31 reversely along the threaded portion 30 of the hollow shaft 29 is controlled by means of the same travelling yoke 90 previously described but at a certain point in its reverse travel, the aforesaid yoke contacts with and bears against the yoke connection 83 attached to the driven part 81 of the reverse clutch to disengage the driven part 81 from the loose part 75 of the reverse clutch.

If desired, the speed at which the boring elements are fed toward and away from the breast of coal or mineral may be increased or decreased as desired. This may be done by shifting gear 49 into engagement with either of complementary pairs of gears 38 and 44, 39 and 45, 41 and 47, or 42 and 48. The shifting of gear 49 is effected by pulling outwardly on the knob 62 and then turning such knob in such direction that the forked bearing 52 will slide along the track 53 to the desired extent by means of pin 57 and arm 56. The gear 49 is then locked in its adjusted position by means of arm 59 and pin 60 as clearly shown in Figure 20.

When the boring elements have been retracted to their initial feeding position the operator pushes the mast 146 to an extent sufficient to shift the apparatus to a point such that the boring elements are in position to attack another multiple of the breast along the juncture point of the breast and floor of the vein, and repeats the feeding and withdrawing operations of the boring elements previously described. This is continued until a fissure has been formed which extends partially or completely across the breast at this point. Preferably, a fissure is formed which extends completely across the breast at this point. As the boring elements bore at an angle, the borings are picked up by the spiral portion and are conveyed back toward the working space of the vein and discharged upon the pitched floor. The formation of such fissure severs the coal from the bed rock of the floor.

Upon completion of the fissure to the desired extent at the base of the breast, the operator turns the hand wheel 141 in the proper direction to a degree sufficient to cause the sleeve 36 to rotate within the sleeve 136, and thereby move the boring elements to a position such that they are in a vertical plane. Then the operator pushes the mast 146 to the left or right so as to bring the boring elements 3 in a position in line with the line of joinder between a lateral rib and the breast, whereupon the hand wheel 190 is turned in the proper direction so as to raise the apparatus to a point such that the boring elements will attack a multiple of the breast in a vertical plane which is at an angle substantially parallel with the pitch 75

of the floor of the vein. Of course, these two operations may be performed in reverse manner. With the boring elements thus positioned the operator repeats the feeding and withdrawing operations of the boring elements previously described. The apparatus is then elevated by means of the wheel 190 to a position such that the boring elements are approximately just above the portion containing the bored holes but in the same vertical plane, and the feeding and withdrawing operations of the boring elements are again repeated. This is repeated successively until the coal or mineral along the lateral rib has been punctured from the floor to the roof of the vein. When this has been completed, the coal along the opposite lateral rib may be punctured from the floor to the roof in the same manner or the operator may proceed with the succeeding step in the method described herein below immediately after the coal has been punctured along one of the lateral ribs. Preferably, the coal along both of the lateral ribs is punctured before proceeding with such succeeding step. The boring of holes in the coal of the breast along the lateral ribs from the floor to the roof of the vein fractures the cleavage of the coal at such points.

Upon completion of the step of fracturing the cleavage of the coal along the lateral ribs, the operator turns the hand wheel 141 in the proper direction to a degree sufficient to cause the sleeve 36 to rotate within the sleeve 136, and thereby move the boring elements to a position such that they are in a horizontal plane. The nut 153 is then turned in the proper direction to tilt the apparatus upwardly so that the boring elements will be in a horizontal plane which is at an angle substantially parallel with the pitch of the floor of the vein. Then, the hand wheel 190 is turned in the proper direction so as to lower the apparatus to a point such that the boring elements will be at a point spaced from the fissure, whereupon the mast 146 is pushed to the right or left to shift the apparatus to a point such that the boring elements are in position to attack a multiple of the working breast extending from either one of the two lateral ribs or intermediate the two ribs. It is preferred to shift the apparatus to a point such that the boring elements will attack a multiple of the working breast extending either from the right or left hand lateral rib. At this point the operator repeats the feeding operations of the boring elements into the face of the breast as previously described. When the boring has progressed to the point where the boring elements have penetrated into the coal to the partial or full extent of their length, the operator grasps the hand wheel 134 and exerts a pull backwardly thereon to cause the loose part 123 of the clutch to engage with the driven part 125 of the clutch and thereby actuate the expansive force inducing elements. Preferably the actuation of the expansive force inducing elements is effected when the boring elements have penetrated to a point substantially corresponding to their entire length. The engagement of the aforesaid parts of the clutch causes the rotation of each of the rods 99 through the sprocket wheels 117 carried by each of said rods. As shown in Figure 11 the sprocket wheels are in meshing engagement with a sprocket chain 118 which is driven by sprocket wheel 119. As the rods 99 are rotated the pointed nose 104 of each of the squared nuts 103 are moved forwardly into contact with the inner surfaces of the jaw members 108 and 109 and press

against such members to such a degree as to cause the jaw members to extend outwardly through the opposed slots 96, 97, and 98 in the tube 95 and bear against the V-shaped walls of the interconnecting passages of the spaced localized areas. The pressing of the jaw members against the V-shaped walls of the interconnecting passages of the spaced localized areas induce expansive forces to be exerted upon the coal in the region of such areas which in themselves and unsupplemented by any auxiliary disruptive forces are of sufficient magnitude to break away and dislodge the coal or mineral in the region of such areas in sizable pieces with a minimum of fines and undersized particles. In other words, these expansive forces break away and dislodge the coal in the space bounded by the fissure and the portion of the plane in which the spaced localized areas are being formed. It is to be noted that the extent of rotation of the rods 99 is controlled by a nut 129 travelling along the threaded portion 127 of rod 126. By reference to Figures 24 and 25 it will be apparent that as the rod 126 rotates the nut 129 travels backwardly along the threaded portion 127 until it contacts with the end of sleeve 120 whereupon the loose part 123 of the clutch is pulled out of engagement with the driven part 125 and stops the rotation of the rod 126 and rods 99. As soon as the rotation of the rods 126 and rods 99 is stopped, the operator turns the wheel 134 in the opposite direction to cause the nut 129 to move reversely along the threaded portion 127 of rod 126 and rotate the rods 99 in the opposite direction through the same sprocket and chain gearing previously described for rotating the rods 99 in the forward direction thereby retracting the jaw members 108 and 109 to their normal position. At this point the operator repeats the withdrawing operation of the boring elements.

In place of only rotating the rods 99 to actuate the expansive force inducing elements, the rods may be rotated to effect the actuation of said elements and during the rotation thereof vibratory forces applied to said elements by means of hammer blows imparted to the ends of said rods by the modification shown in Figures 32 and 33. The end of the rod 126 extending into the housing 2 is connected by a yoke 209 and pin 210 to a fixed part 211 of a friction disk clutch carried by the shaft 11. The fixed part 211 cooperates with a loose part 212 of a friction disk clutch which is also carried by shaft 11. Secured to the loose part 212 of the clutch is a gear 213 which meshes with a gear 214 carried by a stub shaft 215. The shaft 215 also carries a worm 216 which meshes with a worm wheel 217 carried by a hexagonal shaped shaft 218. Rotatably mounted on the shaft 218 are a plurality of cams 219, each of which engage with and ride upon a roller 220 rotatably mounted on a pin 221. Fixedly mounted upon a hexagonal shaft 222 are mounted a plurality of levers 223, each of which contact with and bear against the end of each of rods 99. As the roller 220 rides about the peripheral surface of the cam 219 it exerts pressure on the roller at certain points of the orbital travel of the cam to such an extent as to cause the lever 223 to overcome the force exerted thereon by the spring 224 and then abruptly release such pressure. The application of the pressure to such extent upon the lever 223 through the roller 220 so as to overcome the tensile stress or force exerted thereon by the spring 224 induces the hammer pin 225 to be

- 5 moved away from the complementary end of the rod 99, and the abrupt release of such application of pressure causes the hammer pin 225 to strike against the complementary end of the rod 99 to exert a vibratory force which is distributed to the coal or mineral in the region of contact of the expansive force inducing members when said members are operating in the coal or mineral.
- 10 The shaft 218 also has rotatably mounted thereon a plurality of worm wheels 225, each of which mesh with a worm 226 rotatably mounted on the rod 99 to thereby rotate the rods 99 and actuate the expansive force inducing elements.
- 15 When the boring elements have been retracted to their initial feeding position, the operator pushes the mast 146 to an extent sufficient to shift the apparatus to a point such that the boring elements are in position to attack another 20 multiple of the breast adjacent the portion just broken away and dislodged. It is to be understood that the boring elements are merely moved to a position in the same plane and still are positioned at an angle substantially parallel to the 25 pitch of the floor of the vein. The operator then repeats the feeding and withdrawing operations of the boring elements and actuates the expansive force inducing elements during the feeding operation of the boring elements as previously 30 described. This is continued until the coal has been broken away and dislodged clear across this plane. The operator then shifts the boring elements to a plane above and spaced from the first plane and then causes such elements to operate 35 in turn upon multiple portions of the breast along such plane until the coal or mineral bounded by such plane and the first plane has been mined. This is continued until all of the coal or mineral in the face of the breast has been broken away 40 and dislodged.
- 40 After the entire face of the breast has been mined, the carriage 166 supporting the mast 146 carrying the apparatus is moved forward along the tracks 192 by means of the jacks 201 to a 45 position such that the apparatus can again attack the breast of coal in the manner previously described.
- Having fully described the invention, what I claim as new and desire to secure by Letters 50 Patent is:
1. The method of pitch mining of coal or similar minerals without blasting which comprises forming a fissure in the breast at an angle substantially parallel to the pitch of the floor 55 at the juncture point of the breast and the floor of the vein, fracturing the cleavage of the coal or mineral from the floor to the roof of said vein along the joinder point of a lateral rib and the breast, forming contiguous communicating areas 60 of a depth substantially corresponding to said fissure in the breast in a plane spaced from said fissure and at an angle substantially parallel to the pitch of the floor of the vein, and applying to the walls of said areas at points intermediate the axes of said areas expansive forces which in themselves are of sufficient magnitude to break away and dislodge the coal or mineral in the region of said areas in sizable pieces with a minimum of fines and undersized particles.
- 65 2. The method of pitch mining of coal or similar minerals without blasting which comprises forming a fissure in the breast at an angle substantially parallel to the pitch of the floor at the juncture point of the breast and the floor of the 70 vein, fracturing the cleavage of the coal or mineral from the floor to the roof of said vein along each of the joinder points of the lateral ribs and the breast, forming contiguous communicating areas of a depth substantially corresponding to said fissure in the breast in a plane spaced from said fissure and at an angle substantially parallel to the pitch of the floor of the vein, and applying to the walls of said areas expansive forces which in themselves are of sufficient magnitude to break away and dislodge the coal or mineral in the region of said areas in sizable pieces with a minimum of fines and undersized particles.
- 75 3. The method of pitch mining of coal or similar minerals without blasting which comprises forming a fissure in the breast extending across the entire face of the breast at an angle substantially parallel with the pitch of the floor at the juncture point of the breast and the floor of the vein, fracturing the cleavage of the coal or mineral from the floor to the roof of said vein along each of the joinder points of the lateral ribs and the breast, forming contiguous communicating areas of a depth substantially corresponding to said fissure in the breast in a plane spaced from said fissure and at an angle substantially parallel to the pitch of the floor of the vein, and applying to the walls of said areas expansive forces which in themselves are of sufficient magnitude to break away and dislodge the coal or mineral in the region of said areas in sizable pieces with a minimum of fines and undersized particles.
- 80 4. The method of pitch mining of coal or similar minerals without blasting which comprises forming a fissure in the breast extending across the entire face of the breast at an angle substantially parallel with the pitch of the floor at the juncture point of the breast and the floor of the vein, fracturing the cleavage of the coal or mineral from the floor to the roof of said vein along each of the joinder points of the lateral ribs and the breast, forming contiguous communicating areas of a depth substantially corresponding to said fissure in the breast in a plane spaced from said fissure and at an angle substantially parallel to the pitch of the floor of the vein, and applying to the walls of said areas expansive forces which in themselves are of sufficient magnitude to break away and dislodge the coal or mineral in the region of said areas in sizable pieces with a minimum of fines and undersized particles.
- 85 5. The method of pitch mining of coal or similar minerals without blasting which comprises forming a fissure in the breast extending across the entire face of the breast at an angle substantially parallel with the pitch of the floor at the juncture point of the breast and the floor of the vein, fracturing the cleavage of the coal or mineral from the floor to the roof of said vein along each of the joinder points of the lateral ribs and the breast, forming contiguous communicating areas of a depth substantially corresponding to said fissure in the breast in a plane spaced from said fissure and at an angle substantially parallel to the pitch of the floor of the vein, and applying to the walls of said areas expansive and vibratory forces which in themselves are of sufficient magnitude to break away and dislodge the coal or mineral in the region of said areas in sizable pieces with a minimum of fines and undersized particles.

6. The method of pitch mining of coal or similar minerals without blasting which comprises forming a fissure in the breast extending across the entire face of the breast at an angle substantially parallel with the pitch of the floor at the juncture point of the breast and the floor of the vein, fracturing the cleavage of the coal or mineral from the floor to the roof of said vein along each of the joinder points of the lateral ribs and the breast, forming contiguous communicating areas of a depth substantially corresponding to said fissure in the breast in a plane spaced from said fissure and at an angle substantially parallel to the pitch of the floor of the vein, and applying to the walls of said areas at points intermediate the axes of said areas intermittent expansive and vibratory forces which in themselves are of sufficient magnitude to break away and dislodge the coal or mineral in the region of said areas in sizable pieces with a minimum of fines and undersized particles.

minimum of fines and undersized particles.

7. The method of pitch mining of coal or similar minerals without blasting which comprises forming a fissure in the breast extending across 25 the entire face of the breast at an angle substantially parallel with the pitch of the floor at the juncture point of the breast and the floor of the vein, fracturing the cleavage of the coal or mineral from the floor to the roof of said vein 30 along each of the joinder points of the lateral ribs and the breast, forming contiguous communicating areas of a depth substantially corresponding to said fissure across the entire breast in a plane spaced from said fissure and at an 35 angle substantially parallel to the pitch of the floor of the vein, and applying to the walls of said areas at points intermediate the axes of said areas expansive forces which in themselves and unsupplemented by any auxiliary disruptive 40 forces are of sufficient magnitude to break away and dislodge the coal or mineral in the region of said areas in sizable pieces with a minimum of fines and undersized particles.

8. The method of pitch mining of coal or similar minerals without blasting which comprises forming a fissure in the breast extending across the entire face of the breast at an angle substantially parallel with the pitch of the floor at the juncture point of the breast and the floor of the vein, fracturing the cleavage of the coal or mineral from the floor to the roof of said vein along each of the joinder points of the lateral ribs and the breast, forming contiguous communicating areas of a depth substantially corresponding to said fissure across the entire breast in a plane spaced from said fissure and at an angle substantially parallel to the pitch of the floor of the vein, and applying to the walls of said areas at points intermediate the axes of said areas intermittent expansive forces which in themselves and unsupplemented by any auxiliary disruptive forces are of sufficient magnitude to break away and dislodge the coal or mineral in the region of said areas in sizable pieces with a minimum of fines and undersized particles.

9. The method of pitch mining of coal or similar minerals without blasting which comprises forming a fissure in the breast extending across the entire face of the breast at an angle substantially parallel with the pitch of the floor at the juncture point of the breast and the floor of the vein, fracturing the cleavage of the coal or mineral from the floor to the roof of said vein along each of the joinder points of the lateral ribs and the breast, forming contiguous communicating

areas of a depth substantially corresponding to said fissure across the entire breast in a plane spaced from said fissure and at an angle substantially parallel to the pitch of the floor of the vein, and applying to the walls of said areas at points intermediate the axes of said areas expansive and vibratory forces which in themselves and un-supplemented by any auxiliary disruptive forces are of sufficient magnitude to break away and dislodge the coal or mineral in the region of said areas in sizable pieces with a minimum of fines and undersized particles.

10. The method of pitch mining of coal or similar minerals without blasting which comprises forming a fissure in the breast extending across the entire face of the breast at an angle substantially parallel with the pitch of the floor at the juncture point of the breast and the floor of the vein, fracturing the cleavage of the coal or mineral from the floor to the roof of said vein along each of the joinder points of the lateral ribs and the breast, forming contiguous communicating areas of a depth substantially corresponding to said fissure across the entire breast in a plane spaced from said fissure and at an angle substantially parallel to the pitch of the floor of the vein, and applying to the walls of said areas at points intermediate the axes of said areas intermittent expansive and vibratory forces which in themselves and unsupplemented by any auxiliary disruptive forces are of sufficient magnitude to break away and dislodge the coal or mineral in the region of said areas in sizable pieces with a minimum of fines and undersized particles. 15 20 25 30

11. The method of pitch mining of coal or similar minerals without blasting which comprises forming a fissure in the breast extending across the entire face of the breast at an angle substantially parallel with the pitch of the floor at the juncture point of the breast and the floor of the vein, fracturing the cleavage of the coal or mineral from the floor to the roof of said vein along each of the joinder points of the lateral ribs and the breast, forming contiguous communicating areas of a depth substantially corresponding to said fissure across the entire breast in a plane spaced from said fissure and at an angle substantially parallel to the pitch of the floor of the vein, applying to the walls of said areas at points intermediate the axes of said areas expansive forces which in themselves and unsupplemented by any auxiliary disruptive forces are of sufficient magnitude to break away and dislodge the coal or mineral in the region of said areas in sizable pieces with a minimum of fines and undersized particles, and continuing the formation of contiguous communicating areas in other planes spaced from said fissure and the application of expansive forces to the walls of said areas at points intermediate the axes of said areas until the entire face of the breast of coal or mineral has been broken away and dislodged.

angle substantially parallel to the pitch of the floor of the vein, applying to the walls of said areas at points intermediate the axes of said areas expansive and vibratory forces which in themselves and unsupplemented by any auxiliary disruptive forces are of sufficient magnitude to break away and dislodge the coal or mineral in the region of said areas in sizable pieces with a minimum of fines and undersized particles.

5 and continuing the formation of contiguous communicating areas in other planes spaced from said fissure and the application of expansive and vibratory forces to the walls of said areas at points intermediate the axes of said areas until

10 the entire face of the breast of coal or mineral has been broken away and dislodged.

15

13. The method of pitch mining of coal or similar minerals without blasting which comprises boring a fissure in the breast at an angle substantially parallel to the pitch of the floor at the juncture point of the breast and the floor of the vein, boring into the coal or mineral along the joinder point of a lateral rib and the breast to fracture the cleavage of the coal or mineral, boring contiguous communicating areas of a depth substantially corresponding to said fissure in the breast in a plane spaced from said fissure and at an angle substantially parallel to the pitch of the floor of the vein, and applying to the walls

20 of said areas at points intermediate the axes of said areas during the boring thereof expansive forces which in themselves are of sufficient magnitude to break away and dislodge the coal or mineral in the region of said areas in sizable

25 pieces with a minimum of fines and undersized particles.

14. The method of pitch mining of coal or similar minerals without blasting which comprises boring a fissure in the breast at an angle substantially parallel to the pitch of the floor at the juncture point of the breast and the floor of the vein, boring into the coal or mineral along the joinder point of a lateral rib and the breast to fracture the cleavage of the coal or mineral, boring contiguous communicating areas of a depth substantially corresponding to said fissure in the breast in a plane spaced from said fissure and at an angle substantially parallel to the pitch of the floor of the vein, and applying to the walls

30 of said areas at points intermediate the axes of said areas during the boring thereof expansive forces which in themselves are of sufficient magnitude to break away and dislodge the coal or mineral in the region of said areas in sizable

35 pieces with a minimum of fines and undersized particles.

15. The method of pitch mining of coal or similar minerals without blasting which comprises

boring a fissure in the breast extending across

40 the entire face of the breast at an angle substantially parallel with the pitch of the floor at the juncture point of the breast and the floor of the vein, boring into the coal or mineral from the floor to the roof of the vein along each of the

45 joinder points of the lateral ribs and the breast to fracture the cleavage of the coal or mineral, boring contiguous communicating areas of a depth substantially corresponding to said fissure in the breast in a plane spaced from said fissure

50 and at an angle substantially parallel to the pitch of the floor of the vein, and applying to the walls of said areas at points intermediate the axes of said areas during the boring thereof expansive forces which in themselves are of sufficient

55 magnitude to break away and dislodge the coal or mineral in the region of said areas in sizable pieces with a minimum of fines and undersized particles.

60

16. The method of pitch mining of coal or similar minerals without blasting which comprises

boring a fissure in the breast extending across the entire face of the breast at an angle substantially parallel with the pitch of the floor at the juncture point of the breast and the floor of the vein, boring into the coal or mineral from the floor to the roof of the vein along each of the

65 joinder points of the lateral ribs and the breast to fracture the cleavage of the coal or mineral, boring contiguous communicating areas of a depth substantially corresponding to said fissure in the breast in a plane spaced from said fissure

70 and at an angle substantially parallel to the pitch of the floor of the vein, and applying to the walls of said areas at points intermediate the axes of said areas until

75

mineral in the region of said areas in sizable pieces with a minimum of fines and undersized particles.

16. The method of pitch mining of coal or similar minerals without blasting which comprises boring a fissure in the breast extending across the entire face of the breast at an angle substantially parallel with the pitch of the floor at the juncture point of the breast and the floor of the vein, boring into the coal or mineral from the floor to the roof of the vein along each of the

80 joinder points of the lateral ribs and the breast to fracture the cleavage of the coal or mineral, boring contiguous communicating areas of a depth substantially corresponding to said fissure in the breast in a plane spaced from said fissure and at an angle substantially parallel to the pitch of the floor of the vein, and applying to the walls of said areas at points intermediate the axes of said areas during the boring thereof expansive and vibratory forces which in themselves are of sufficient magnitude to break away and dislodge the coal or mineral in the region of said areas in sizable pieces with a minimum of fines and undersized particles.

85

17. The method of pitch mining of coal or similar minerals without blasting which comprises boring a fissure in the breast extending across the entire face of the breast at an angle substantially parallel with the pitch of the floor at the juncture point of the breast and the floor of the vein, boring into the coal or mineral from the floor to the roof of the vein along each of the

90 joinder points of the lateral ribs and the breast to fracture the cleavage of the coal or mineral, boring contiguous communicating areas of a depth substantially corresponding to said fissure across the entire breast in a plane spaced from said fissure and at an angle substantially parallel to the pitch of the floor of the vein, and applying to the walls of said areas at points intermediate the axes of said areas expansive forces which in themselves and unsupplemented by any auxiliary disruptive forces are of sufficient magnitude to break away and dislodge the coal or mineral in the region of said areas in sizable

95 pieces with a minimum of fines and undersized particles.

18. The method of pitch mining of coal or similar minerals without blasting which comprises boring a fissure in the breast extending across the entire face of the breast at an angle substantially parallel with the pitch of the floor at the juncture point of the breast and the floor of the vein, boring into the coal or mineral from the floor to the roof of the vein along each of the

100 joinder points of the lateral ribs and the breast to fracture the cleavage of the coal or mineral, boring contiguous communicating areas of a depth substantially corresponding to said fissure across the entire breast in a plane spaced from said fissure and at an angle substantially parallel to the pitch of the floor of the vein, applying to the walls of said areas at points intermediate the axes of said areas expansive forces which in themselves and unsupplemented by any auxiliary disruptive forces are of sufficient magnitude to break away and dislodge the coal or mineral in the region of said areas in sizable pieces with a minimum of fines and undersized particles, and continuing the formation of contiguous communicating areas in other planes spaced from said fissure and the application of expansive forces to the walls of said areas at points intermediate the axes of said areas until

105

the entire face of the breast of coal or mineral has been broken away and dislodged.

19. The method of pitch mining of coal or similar minerals without blasting which comprises boring a fissure in the breast extending across the entire face of the breast at an angle substantially parallel with the pitch of the floor at the juncture point of the breast and the floor of the vein, boring into the coal or mineral from the floor to the roof of the vein along each of the joinder points of the lateral ribs and the breast to fracture the cleavage of the coal or mineral, boring contiguous communicating areas of a depth substantially corresponding to said fissure across the entire breast in a plane spaced from said fissure and at an angle substantially parallel to the pitch of the floor of the vein, and applying to the walls of said areas at points intermediate the axes of said areas expansive and vibratory forces which in themselves and unsupplemented by any auxiliary disruptive forces are of sufficient magnitude to break away and dislodge the coal or mineral in the region of said areas in sizable pieces with a minimum of fines and undersized particles.

20. The method of pitch mining of coal or similar minerals without blasting which comprises boring a fissure in the breast extending across the entire face of the breast at an angle substantially parallel with the pitch of the floor at the juncture point of the breast and the floor of the vein, boring into the coal or mineral from the floor to the roof of the vein along each of the joinder points of the lateral ribs and the breast to fracture the cleavage of the coal or mineral, boring contiguous communicating areas of a depth substantially corresponding to said fissure across the entire breast in a plane spaced from said fissure and at an angle substantially parallel to the pitch of the floor of the vein, applying to the walls of said areas at points intermediate the axes of said areas expansive and vibratory forces which in themselves and unsupplemented by any auxiliary disruptive forces are of sufficient magnitude to break away and dislodge the coal or mineral in the region of said areas in sizable pieces with a minimum of fines and undersized particles, and continuing the formation of contiguous communicating areas in other planes spaced from said fissure and the application of expansive and vibratory forces to the walls of said areas at points intermediate the axes of said areas until the entire face of the breast of coal or mineral has been broken away and dislodged.

21. Apparatus for the mining of coal or similar mineral comprising a plurality of rotatable boring elements arranged in spaced and aligned relation for boring contiguous communicating areas in the face of a breast of coal or mineral which has an undercut at the juncture point of the floor and breast and a side cut along the joinder point of a lateral rib and breast in a plane substantially parallel with the pitch of the floor of the vein and spaced from said undercut, and means in association with said boring elements for applying to the walls of said areas at points intermediate the axes of said boring elements expansive forces which in themselves are of such magnitude as to break away the coal or mineral in the region of such areas in sizable pieces with a minimum of fines and undersized particles.

22. Apparatus for the mining of coal or similar mineral comprising a plurality of rotatable boring elements arranged in spaced and aligned re-

lation for boring contiguous communicating areas in the face of a breast of coal or mineral which has an undercut at the juncture point of the floor and breast and a side cut along the joinder point of a lateral rib and breast in a plane substantially parallel with the pitch of the floor of the vein and spaced from said undercut, and means in association with said boring elements for applying to the walls of said areas at points intermediate the axes of said boring elements both expansive and vibratory forces which in themselves are of such magnitude as to break away the coal or mineral in the region of such areas in sizable pieces with a minimum of fines and undersized particles.

23. Apparatus for the mining of coal or similar mineral comprising a plurality of rotatable boring elements arranged in spaced and aligned relation for boring contiguous communicating areas in the face of a breast of coal or mineral which has an undercut at the juncture point of the floor and breast and a side cut along the joinder point of a lateral rib and breast in a plane substantially parallel with the pitch of the floor of the vein and spaced from said undercut, means embodying expansible jaw members in association with said boring elements, and means for causing said jaw members to press against the walls of said areas at points intermediate the axes of said boring elements thereby exerting expansive forces upon the walls of each of said areas which in themselves are of such magnitude as to break away the coal or mineral in the region of such areas in sizable pieces with a minimum of fines and undersized particles.

24. Apparatus for the mining of coal or similar mineral comprising a plurality of rotatable boring elements arranged in spaced and aligned relation for boring contiguous communicating areas in the face of a breast of coal or mineral which has an undercut at the juncture point of the floor and breast and a side cut along the joinder point of a lateral rib and breast in a plane substantially parallel with the pitch of the floor of the vein and spaced from said undercut, means embodying expansible jaw members in association with said boring elements, means for causing said jaw members to press against the walls of said areas at points intermediate the axes of said boring elements, and means in association with said jaw members for applying hammer blows thereto thereby exerting expansive and vibratory forces upon the walls of said areas at points intermediate the axes of said areas which in themselves are of such magnitude as to break away the coal or mineral in the region of such areas in sizable pieces with a minimum of fines and undersized particles.

25. Apparatus for the mining of coal or similar mineral comprising a plurality of rotatable boring elements arranged in spaced and aligned relation for boring contiguous communicating areas in the face of the breast of coal or mineral, means embodying expansible jaw members in association with said boring elements, means for expanding said jaw members to cause said members to press against the walls of said areas at points intermediate the axes of said boring elements, means for supporting said elements and jaw members as a unit in the vein adjacent the face of the breast of coal or mineral, means for shifting said elements and jaw members as a unit to a position such that the boring elements will be in a plane which is substantially parallel with the pitch of the floor of the vein, means

for shifting said supporting means to a position such that the boring elements in their adjusted position will be at or spaced from the juncture point of the floor and breast or at a point along the juncture point of a lateral rib and breast, means for feeding said boring elements while in such adjusted position toward and away from the breast, and means for applying hammer blows to said jaw members during the feeding of said 10 boring elements toward the breast.

26. Apparatus for the mining of coal or similar mineral comprising a plurality of rotatable boring elements arranged in spaced and aligned relation, means for supporting said elements as a 15 unit in the vein adjacent the face of the breast of coal or mineral, means for shifting said elements as a unit to a position such that the boring elements will be in a plane which is substantially parallel with the pitch of the floor of the vein, means for shifting said supporting means to a position such that the boring elements in their adjusted position will be at or spaced from the juncture point of the floor and breast or at a point along the juncture point of a lateral rib and breast, means for rotating said boring elements, and means for feeding said boring elements while in such adjusted position at a predetermined rate toward the breast, said feeding means embodying a shaft comprising a threaded 25 portion and a non-threaded portion, a nut mounted on said threaded portion for travel therealong, a sleeve carrying said boring elements secured to said nut, a nest of gears of varying diameters carried by the non-threaded portion of said shaft, 30 a second shaft, a nest of gears of varying diameters arranged in reverse complementary relation with respect to the nest of gears on said first-named shaft carried by said second shaft, a loose shaft carrying a gear shiftable to a position such that it will mesh with any pair of opposed gears of the aforesaid nests of gears, and means for rotating said second-named shaft.

27. Apparatus for the mining of coal or similar mineral comprising a plurality of rotatable boring elements arranged in spaced and aligned relation, means for supporting said elements as a unit in the vein adjacent the face of the breast of coal or mineral, means for shifting said elements as a unit to a position such that the boring elements will be in a plane which is substantially parallel with the pitch of the floor of the vein, means for shifting said supporting means to a position such that the boring elements in their adjusted position will be at or spaced from the juncture point of the floor and breast or at a point along the juncture point of a lateral rib and breast, means for rotating said boring elements, and means for feeding said boring elements while in such adjusted position at a predetermined rate 40 toward and away from the breast, said feeding means embodying a shaft comprising a threaded portion and a non-threaded portion, a nut mounted on said threaded portion for travel therealong, a sleeve carrying said boring elements secured to said nut, a nest of gears of varying diameters carried by the non-threaded portion of said shaft, a second shaft, a nest of gears of varying diameters arranged in reversed complementary relation with respect to the nest of gears on said first-named shaft carried by said second shaft, a loose shaft carrying a gear shiftable to a position such that it will mesh with any pair of opposed gears of the aforesaid nests of gears, and means for rotating said second-named shaft in one direction, means operatively connected to said second-named shaft for stopping the rotation thereof when the boring elements have penetrated into the breast to the desired extent, means for rotating said second-named shaft in the opposite direction until the boring elements have returned to their initial feeding position, and means for stopping the rotation of said second-named shaft when the boring elements have reached their initial feeding position.

said second-named shaft for stopping the rotation thereof when the boring elements have penetrated into the breast to the desired extent, and means for rotating said second-named shaft in the opposite direction until the boring elements have returned to their initial feeding position.

28. Apparatus for the mining of coal or similar mineral comprising a plurality of rotatable boring elements arranged in spaced and aligned relation, means for supporting said elements as a unit in the vein adjacent the face of the breast of coal or mineral, means for shifting said elements as a unit to a position such that the boring elements will be in a plane which is substantially parallel with the pitch of the floor of the vein, means for shifting said supporting means to a position such that the boring elements in their adjusted position will be at or spaced from the juncture point of the floor and breast or at a point along the juncture point of a lateral rib and breast, means for rotating said boring elements, and means for feeding said boring elements while in such adjusted position at a predetermined rate toward and away from the breast, said feeding means embodying a shaft comprising a threaded portion and a non-threaded portion, a nut mounted on said threaded portion for travel therealong, a sleeve carrying said boring elements secured to said nut, a nest of gears of varying diameters carried by the non-threaded portion of said shaft, a second shaft, a nest of gears of varying diameters arranged in reversed complementary relation with respect to the nest of gears on said first-named shaft carried by said second shaft, a loose shaft carrying a gear shiftable to a position such that it will mesh with any pair of opposed gears of the aforesaid nests of gears, means for rotating said second-named shaft in one direction, means operatively connected to said second-named shaft for stopping the rotation thereof when the boring elements have penetrated into the breast to the desired extent, means for rotating said second-named shaft in the opposite direction until the boring elements have returned to their initial feeding position, and means for stopping the rotation of said second-named shaft when the boring elements have reached their initial feeding position.

29. Apparatus for the mining of coal or similar mineral comprising a housing, a plurality of rotatable boring elements arranged in spaced and aligned relation mounted in said housing and having an end extended through a wall thereof, a carriage, means on said carriage for supporting said housing, means for shifting said housing as a unit to a position such that the boring elements will be in a plane which is substantially parallel with the pitch of the floor of the vein, means for shifting said supporting means to a position such that the boring elements in their adjusted position will be at or spaced from the juncture point of the floor and breast or at a point along the juncture point of a lateral rib and breast, means for feeding said housing while in such adjusted position toward and away from the breast, tracks for said carriage, means for operatively connecting said carriage to said tracks, and means for moving said carriage along said tracks.

30. Apparatus for the mining of coal or similar mineral comprising a housing, a plurality of rotatable boring elements arranged in spaced and aligned relation mounted in said housing and having an end extended through a wall thereof,

a carriage, means on said carriage for supporting said housing, means for shifting said housing as a unit to a position such that the boring elements will be in a plane which is substantially 5 parallel with the pitch of the floor of the vein, means for shifting said supporting means to a position such that the boring elements in their adjusted position will be at or spaced from the juncture point of the floor and breast or at a 10 point along the juncture point of a lateral rib and breast, means for rotating said boring elements, means for feeding said boring elements while in such adjusted position at a predetermined rate toward the breast, means for stopping said feeding means when the boring elements have penetrated into the breast to the 15 desired extent, means for returning said boring elements to their initial feeding position, tracks for said carriage, means for operatively connecting said carriage to said tracks, and means for moving said carriage along said tracks.

31. In an apparatus for the mining of coal or similar mineral, a housing, a plurality of rotatable boring elements arranged in spaced and 25 aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting collar carried by said tubular member, a mast, a bearing collar on said mast, a forked member having a threaded handle connecting said supporting collar to said bearing 30 collar, a nut movable for travel along said threaded handle and adapted to bear against said bearing collar whereby rotation of such nut causes the tubular member to be tilted to a position such that the boring elements will be in a 35 plane which is substantially parallel with the pitch of the floor of the vein, and means for shifting said tubular member to a position such that the boring elements in their adjusted position will be at or spaced from the juncture point 40 of the floor and breast or at a point along the juncture point of a lateral rib and breast.

32. In an apparatus for the mining of coal or similar mineral, a housing, a plurality of rotatable boring elements arranged in spaced and 50 aligned relation mounted in said housing and having an end extending through a wall thereof, a casing enclosing a gear mechanism, a tubular member enclosing the actuating mechanism connecting said boring elements to said gear mechanism interposed between said housing and said casing, means for shifting said tubular member to a position such that the boring elements will be in a plane which is substantially parallel 55 with the pitch of the floor of the vein, a sleeve rotatably mounted on said tubular member, a mast, a supporting collar carried by said mast, means for securing said sleeve to said supporting collar, a threaded nut carried by said collar, a hollow tube, a threaded rod extending through said nut and said tube and keyed to said tube, a gear on said hollow tube, and means for rotating said gear in any direction whereby the tubular member will 60 be moved to a position such that the boring elements in their adjusted position will be at or spaced from the juncture point of the floor and breast or at a point along the juncture point of a lateral rib and breast.

33. In an apparatus for the mining of coal or similar mineral, a housing, a plurality of rotatable 65 boring elements arranged in spaced and

aligned relation mounted in said housing and having an end extended through a wall thereof, a casing enclosing a gear mechanism, a tubular member enclosing the actuating mechanism connecting said boring elements to said gear mechanism interposed between said housing and said casing, a sleeve rotatably mounted on said tubular member, a mast, a supporting collar carried by said mast, means for attaching said sleeve to said supporting collar, a gear carried by said sleeve and fixedly secured on said tubular member, means for rotating said gear to thereby rotate said tubular member to a degree such that the boring elements will be in a horizontal or vertical plane, means coacting with said tubular 10 member for holding it in the position to which it has been moved by the rotation of said gear, means for shifting said tubular member to a position such that the boring elements in their adjusted position will be in a plane which is substantially parallel with the pitch of the floor of the vein, and means for shifting said tubular member to a position such that the boring elements in their 15 adjusted position will be at or spaced from the juncture point of the floor and breast or at a point along the juncture point of a lateral rib and breast.

34. In an apparatus for the mining of coal or similar mineral, a housing, a plurality of rotatable boring elements arranged in spaced and 20 aligned relation mounted in said housing and having an end extended through a wall thereof, a casing enclosing a gear mechanism, a tubular member enclosing the actuating mechanism connecting said boring elements to said gear mechanism interposed between said housing and said casing, a supporting collar carried by said tubular member, a mast, a bearing collar on said mast, a forked member having a threaded handle connecting said supporting collar to said bearing 25 collar, a nut movable for travel along said threaded handle and adapted to bear against said bearing collar whereby rotation of such nut causes the tubular member to be tilted to a position such that the boring elements will be in a plane which is substantially parallel with the pitch of the floor of the vein, a sleeve rotatably mounted on said tubular member, a second supporting collar carried by said mast, means for securing said sleeve to said second-named supporting collar, a threaded nut carried by said second-named supporting collar, a hollow tube, a threaded rod extending through said nut and said tube and keyed to said tube, a gear on said hollow tube, and means for rotating said gear in any direction whereby the tubular member will 30 be moved to a position such that the boring elements in their adjusted position will be at or spaced from the juncture point of the floor and breast or at a point along the juncture point of a lateral rib and breast.

35. In an apparatus for the mining of coal or similar mineral, a housing, a plurality of rotatable boring elements arranged in spaced and aligned relation mounted in said housing and having an end extended through a wall thereof, a casing enclosing a gear mechanism, a tubular member enclosing the actuating mechanism connecting said boring elements to said gear mechanism interposed between said housing and said casing, a sleeve rotatably mounted on said tubular member, a mast, a supporting collar carried by said mast, means for attaching said sleeve to said supporting collar, a gear carried by said sleeve and fixedly secured on said tubular mem- 35

ber, means for rotating said gear to thereby rotate said tubular member to a degree such that the boring elements will be in a horizontal or vertical plane, a threaded nut carried by said collar, a hollow tube, a threaded rod extending through said nut and said tube and keyed to said tube, a gear on said hollow tube, means for rotating said gear in any direction to thereby shift the tubular member to a position such that the boring elements in their adjusted position will be at or spaced from the juncture point of the floor and breast or at a point along the juncture point of a lateral rib and breast, a second sup-

porting collar carried by said tubular member, a bearing collar carried by said mast, a forked member having a threaded handle connecting said second-named supporting collar to said bearing collar, a second threaded nut movable for travel along said threaded handle and adapted to bear against said bearing collar whereby rotation of such nut causes the tubular member to be tilted to a position such that the boring elements will be in a plane which is substantially parallel with the pitch of the floor of the vein. 5 10

EDGAR M. CADWALLADER.
